(57) **CLAIM**

The ornamental design for a electric grill, as shown and described.

DESCRIPTION

FIG. 1 is a front perspective view of a electric grill, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an exploded perspective view of the electric grill; and,

FIG. 10 is a perspective view of the electric grill shown in an alternate configuration with the top portion flipped over. The broken lines in the drawings illustrate the portions of the electric grill, which form no part of the claimed design. The dash-dot-dash broken lines in FIGS. 1 and 9 show the boundaries of the enlargements shown in FIG. 9, and form no part of the claimed design.
